UNITED STATES PATENT OFFICE.

MICHAEL CHENCHICK, OF CHICAGO, ILLINOIS.

FLOAT AND THE LIKE.

Application filed March 17, 1928. Serial No. 262,394.

The invention relates to floats and the like and the object of the invention is to provide a float adapted to support the hull of a boat or a similar load.

5 A further object of the invention is to provide a float adapted to carry a comparatively heavy load in relation to its size.

A still further object of the invention is to provide a float having a very great buoyancy and stability, it being practically impossible to upset said float.

10 Other objects of the invention not specifically mentioned will be easily ascertained and understood from the following description and the accompanying drawings forming a part thereof. It is however to be understood, that the invention is not to be limited or restricted to the exact formation and construction shown in the drawings and described in the specification, but that the invention is only to be limited by the scope of the claims appended hereto.

In the drawings:

Fig. 1 is a side view of the float carrying 25 the hull of a boat.

Fig. 2 is a sectional view taken on line 2—2 of Fig. 1.

Fig. 3 is an end view of Fig. 1, and

30 Fig. 4 is a top view of the frame of a slightly modified form of a float according to the present invention.

The main frame of the float has preferably a rectangular shape and consists of a pair of longitudinal members 5 and 6 respectively, 35 and a pair of cross pieces 7 only one whereof is shown in the drawings. Stiffening members may be connected to the different frame members as found desirable and convenient, but since the exact construction of the frame 40 is not a part of the invention, this construction is not described in detail.

As shown best in Fig. 1 the ends of the longitudinal frame members are curved upwardly and adjacent each of its ends each 45 longitudinal member is provided with a hole. Shafts 8 and 9 respectively are received in the corresponding holes and extend cross-wise of the float. A pair of bars 10 are pivotally mounted upon the cross shaft 8, one bar 50 adjacent each longitudinal member, and a pair of bars 11 is mounted in the same way upon the cross shaft 9. The bars 10 and 11 are arranged on the cross shafts in such a manner, that each bar is supported intermediate its ends and at equal distances there-

from. Each pair of bars 10 and 11 is connected with each other by means of a pair of cross shafts 12 and 13 respectively, which shall be called float shafts hereafter in order to distinguish them from the main cross 60 shafts 8 and 9. Adjacent each end of each float shaft a disc 14 is loosely mounted. A plurality of hollow bodies forming air or float chambers are supported by each pair of discs. Each disc is provided with a plurality 65 of holes 15, which are arranged adjacent the circumference of the disc and are distributed at equal distances from each other. Short shafts 16 are journaled in said holes and the outer ends of said short shafts may be somewhat upset to keep the shafts in place. At 70 its inner end each short shaft carries a circular plate 17 having a channel shaped cross section. Each pair of corresponding plates supports a tube 18. Each tube is fastened 75 to the rim of the supporting plate 17 by means of rivets 19 or the like and between the rim and the tube a packing 20 is provided in order to make the air chamber formed by the tube and the two end plates 80 airtight.

Underneath the frame two keel blades 21 are arranged. Each blade being fastened to the frame in any convenient manner, but so that it extends downwardly of said frame 85 and parallel to the longitudinal members thereof. Preferably each blade is arranged adjacent one of said longitudinal members.

On top of the frame any desired structure 90 22 may be provided, which is adapted to support a hull of a boat, a platform, or any other means for receiving a load of human beings, material and so forth.

In Figs. 1 and 3 a float is shown having two sets of air chambers fore and aft, each set 95 consisting of a plurality of air chambers. In Fig. 4 the frame supports only one set of air chambers fore and one set aft. The construction of the float shown in Fig. 4 is practically the same as the construction of the 100 float described above. The only difference between the two floats is, that in the float of Fig. 4 the main cross shafts 8 and 9 do not support bars 10 and 11 respectively, but that these bars and the float cross shafts 12 and 105 13 are omitted, so that the discs 14 are mounted directly upon the main cross shafts.

It is easy to see, that the plurality of air chambers and the manner of arranging these chambers as well as arranging the keel 110

blades greatly stabilize the float according to the present invention and impart a great buoyancy thereto.

What I claim is:

- 5 1. In a device of the class described a cross shaft, a disc loosely mounted adjacent each end of said shaft, each disc having a plurality of holes therein adjacent its circumference, said holes being distributed at equal distances from each other, a short shaft journaled in each of said holes and a cylindrical hollow member supported by each pair of corresponding short shafts, the connection between said cylindrical members and the 10 shafts supporting the same being leakproof.
- 15 2. In a device of the class described a cross shaft, a disc loosely mounted adjacent each end of said shaft, each disc having a plurality of holes therein adjacent its circumference and distributed at equal distances from each other, a short shaft journaled in each of said holes, a disc of channel-shaped cross section at the inner end of each short shaft and a cylindrical hollow member fastened with each of its ends to one of said discs, the 20 chamber formed by said cylindrical member and said two discs being leakproof.

In witness whereof I affix my signature.

MICHAEL CHENCHICK.
